UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND.

SIDE FRAME

Application filed August 23, 1926. Serial No. 130,890.

This invention relates to side frames particularly adapted for railway car trucks, and more especially to cast frames in which flexibility is provided for the tension member 5 where it extends beneath the bolster guide columns and spring plank seat portion of the frame.

The principal object of my invention, generally considered, is the provision of a cast 10 side frame for railway car trucks in which a relatively rigid structure at the ends thereof is provided where the same is connected to journal boxes, or to adapt said frame for connection with journal boxes, said rigid 15 structure taking care of secondary stresses and rigidly uniting the ends of the compression and tension members, said compression and tension members, at intermediate portions thereof, being reduced in depth and 20 spaced by bolster guide columns and a connected spring plank seat portion, said tension member being relatively flexible and extended under said bolster columns and spring plank seat portion, provision being 25 made for longitudinal movement of said tension member when the frame is under stress to minimize secondary stresses.

An object of my invention is the provision of a cast side frame for railway car 30 trucks in which the junctions between the compression and tension members are made relatively rigid and a jaw shaped structure is provided adjacent each end of the frame 35 designed to resist local concentrated stresses received from the journal boxes, the tension member being spaced from the compression member at intermediate portions by bolster guide columns connected at their upper portions to the compression member and at their 40 lower portions to a spring plank seat portion which merely rests on the tension member.

Another object of my invention is the provision of a side frame for railway car trucks 45 in which the compression member is so formed that it is relatively shallow in the center or intermediate portion thereof, is designed to flex to a maximum degree at such point, and is provided with bolster columns 50 connected at their lower ends by a

segment shaped spring plank seat member, said columns and member being formed relatively shallow so that they may accommodate themselves to the flexing movement of the compression member, the tension member extending beneath said spring plank seat portion, provision being made for allowing longitudinal movement of the tension member with respect thereto.

A further object of my invention is the 60 provision of a side frame for railway car trucks in which the compression member, tension member, bolster guide columns and spring plank seat portion are integrally cast with flexibility provided between the tension member and bolster guide columns by 65 such means as a space therebetween, said space being subsequently closed while the frame is either hot or cold by a hydraulic press or filled with molten metal or one or 70 more curved bars inserted in the proper location in the mold before the frame is cast, any of said means providing for a non-rigid or movable junction between the tension member and the spring plank seat portion and 75 bolster guide columns upstanding therefrom, whereby undesired secondary stresses are eliminated at this junction.

Other objects and advantages of the invention relating to the particular arrangement and construction of the various parts will become more apparent as the description proceeds.

Referring to the drawings illustrating my invention, the scope whereof is defined by 85 the appended claims:

Figure 1 is a partial side elevation, shown partly in central longitudinal section, of one embodiment of my improved side frame.

Figure 2 is a plan of the structure illustrated in Figure 1, shown partly in section on the line 2—2 of Figure 1 and partly broken away.

Figures 3 and 4 are transverse sectional views on the correspondingly numbered lines 95 of Figure 1 looking in the direction of the arrows.

Figures 5, 6 and 7 are detailed sectional views on the correspondingly numbered lines 100 of Figure 1.

Figure 8 is a partial side elevation, partly in central longitudinal section, illustrating another embodiment of my invention.

Figure 9 is a transverse sectional view on the line 8—8 of Figure 8 looking in the direction of the arrows.

Figures 10 and 11 are views corresponding, respectively, to Figures 8 and 9 but showing a further modification of my invention.

10 Figure 12 is a fragmentary side elevation of a side frame illustrating a still further embodiment of my invention.

15 Figure 13 is a transverse sectional view on the line 13—13 of Figure 14 illustrating an additional embodiment of my invention.

Figure 14 is a fragmentary side elevation of the embodiment of my invention illustrated in Figure 13.

Referring to the drawings in detail, like parts being designated by like reference characters and first considering the embodiment of my invention illustrated in Figures 1 to 7, inclusive, a side frame 1 is shown which comprises a compression member 2 and a tension member 3, said compression and tension members being rigidly united at their ends and to rigid structures 4, somewhat resembling the heads of wrenches in that they are provided with jaws or are jaw shaped, adapted to extend and embrace journal boxes (not shown) or adapted for integral formation with such journal boxes. These rigid structures 4, at each end of the frame, are formed generally elongated and curved in outline and generally box or U shape in cross section with an inner web 5 serving to extend around a journal box, a portion of which web may be considered as a continuation of the lower web 6 of the tension member, an outer web 7 which may be considered as a continuation of the upper web 8 of the compression member, the outer ends of said web 7 being preferably omitted or partially cut away at the outer ends of the jaw portion 4, and side webs 9 and 10 which may be considered as continuations of the corresponding web portions of the compression and tension members 2 and 3. In the embodiment illustrated, the outer part of the jaw shaped portion 4 is formed with a longitudinal aperture 11 adapted for receiving means for locking an associated journal box in place. The webs 5, 7, 9 and 10 may be braced by internal transversely extending webs or gussets 12.

55 In order to economize in the use of metal in the frame, the vertical sides of the jaw shaped portions 4 of the frame do not directly join the horizontal connecting portions, but are connected thereto by sloping portions 60 which, in effect, cut off the corners of the openings or pockets in which the journal boxes are received. This permits the lower web 6 of the tension member to unite with the jaw shaped portions 4 somewhat lower than 65 otherwise and thereby reduces the moment

arm of the transverse and longitudinal forces received from the journal boxes.

The compression member 2 is preferably formed inverted channel shape in cross section, that is, the sides of the upper web 8 are provided with depending flanges 13, which flanges may be formed at the lower edges thereof with outstanding beads or ribs 14 which extend from beyond the intersection of the compression and tension members to the bolster guide columns 15 which depend from said compression member 2. Between the bolster guide columns 15, the depending flanges 13 may be provided with inside beading or ribbing 16 which gradually increases in depth toward the bolster guide columns 15 until it merges to form the inner webs or bolster guiding portions 17 thereof. The webs 17 are formed with outstanding flanges 18 which may be provided with external beading or ribbing 19 along the free edges thereof formed as a continuation of the beading 14 on the compression member. The bolster guide columns 15 are preferably integrally connected, not only to the compression member, but the lower ends thereof are integrally united by a segment shaped spring supporting or spring plank seat portion 20 provided with a lower curved surface 21 which, in the present embodiment, rests directly on the top of the tension member 3 without being otherwise connected thereto except for the provision of side flanges or ribs 22 extending on opposite sides of the tension member 3, as shown particularly in Figure 3, so that, upon a load being applied to the frame, relative longitudinal movement between the tension member and connected bolster guide columns is permitted, thereby obviating the usual secondary stresses found at such a junction.

The tension member 3 adjacent the ends thereof, where it joins with the compression member 2, is relatively deep, the upstanding flanges 23, which are preferably formed with inside beading or ribbing 24 and in connection with the lower web 6 form a member U shape in cross section, however, preferably decrease in depth toward the central and intermediate portions of the tension member until said tension member is substantially rectangular in cross section where it extends beneath the bolster guide columns 15 and the spring plank seat portion 20. At the same time, in order to preserve the requisite area of metal, the tension member is preferably increased in width, as illustrated particularly in Figure 2.

The compression member decreases in depth toward the central and intermediate portions thereof in a manner similar to the tension member but not to the same extent so that, even at the center thereof, the depending flanges 13 are fairly deep. Such a construction is provided so that the compression member is flexed to a maximum at the central portion thereof and, in order to permit such flex-

ing, the bolster guide columns 15 and spring plank seat portion 20 are formed relatively shallow and wide to accommodate themselves to the movement of the compression member.

Although, in the embodiment illustrated in Figures 1 to 7, inclusive, the side frame is shown in its final or finished form, yet, in order to provide for casting such a frame without the integral union between the tension member and the spring plank seat portion, it is necessary to resort to one of the expedients to be hereinafter described for allowing the shallow and wide intermediate portion of the tension member to remain free from connection with the bolster guide columns and curved portion of the segmental spring plank seat portion while being adapted for supplying the necessary support therefor. In other words, the frame may be cast with a space between the curved lower portion of the spring plank seat and connected bolster guide columns, which space is closed by hydraulic pressure or filled with one or more spacing strips or plates.

Referring now to the embodiment of my invention illustrated in Figures 8 and 9, a portion of a side frame 1^a is shown which is formed by casting a frame substantially the same as illustrated in Figures 1 to 7, inclusive, except that a curved plate 25 is positioned between the curved lower surface of the spring plank seat portion 20^a and the correspondingly curved upper surface of the tension member 3^a. This plate may be applied by casting the frame 1^a with a corresponding space and pouring molten metal into said space to form a plate 25 or, if desired, a solid plate 25 may be placed in the mold and the frame cast around it, said plate chilling the metal but not necessarily fusing thereto so that, in any event, provision is made for sufficient longitudinal tensile motion of the tension member 3^a under stress without imparting the usual secondary stresses to the supported parts of the frame thereabove.

Referring now to the modification of my invention illustrated in Figures 10 and 11, a construction is shown similar to that of Figures 8 and 9 except that, instead of one plate 25 placed in the mold when the frame 1^b is cast, a pair of plates 26 and 27 are used, the engaging surfaces of said plates being preferably smooth and the outside surfaces thereof being unfinished so that, when the frame is cast therearound, provision is made for longitudinal motion between the plates 26 and 27 when the frame is under stress, allowing the tension member 3^b to move, as in the other embodiments.

Referring now to the embodiment of my invention illustrated in Figure 12, a construction is there disclosed which is similar to the foregoing except that, instead of a full flexible connection between the tension member 3^c and the bolster guide columns 15^c and

spring plank seat portion 20^c, a connection which may be termed semi-flexible is provided by having the tension member reduced in depth and increased in width to where it meets the bolster guide columns 15^c at which point it is bifurcated to form portions 28 which join with the outer portions of the spring plank seat portion 20^c and bolster guide columns 15^c and surround or embrace the main or central part of said portion, thereby accomplishing some of the results desired by the other embodiments of my invention. As in the other embodiments, the tension member 3^c is generally U shape in cross section although the bolster guide columns 15^c may be T shape in cross section with the upright web of the T extending between the bifurcated portions 28 of the tension member and the outer ends of the top, although inwardly facing, web or flange of the T merging with said bifurcated portions 28.

Referring now to the embodiment of my invention illustrated in Figures 13 and 14, a construction is disclosed similar to the first embodiment except that the central flexible portion of the tension member 3^d is not received between depending flanges or ribs 22 on the spring plank seat portion but merely engages the lower curved surface 21^d when the same is forced thereagainst by hydraulic pressure or when the space is filled up or closed by molten metal cast therein or curved plates forced therein. The design is otherwise slightly different in that a tension member generally I or T shape in cross section is shown and the bolster guide columns 15^d are generally T shape in cross section.

In all the embodiments, the construction not shown or described may be substantially identical with that of the first embodiment which is shown more fully.

From the foregoing disclosure, it will be apparent that I have devised a side frame which is preferably integrally cast but in which the spring blank seat has been separated entirely from the tension member. Such a separation may be effected by casting the frame with a gap or space between the spring blank and tension member, which gap is closed by passing each frame under a hydraulic press, either hot or cold, in which said gap is subsequently filled in with molten metal or a metal plate forced in place or in which one or more bent plates of steel are inserted in the mold between the spring plank seat and tension member and the frame cast therearound. In connection with the latter alternatives, it should be noted that when one separator is set in the mold, it is preferably not fused to either portion of the casting with which it is in contact so that full flexibility is provided, there being no physical connection between the tension member and the spring plank seat portion except substantially vertical contact. When two separators,

however, are employed, each may be fused to its respective portion of the casting, the separators themselves providing definite smooth engaging surfaces between the cooperating members.

Having now described my invention, I claim:

1. A cast side frame comprising compression, tension and bolster column members, said compression member being integrally connected to the bolster columns and the ends of tension member, and the tension member extending between its connections with the compression member freely beneath the bolster columns to form a support therefor.
2. A side frame comprising compression, tension and bolster column members, said compression member being rigidly united to the tension member adjacent the ends thereof and both of said members decreasing in depth toward the center of the frame, the compression member being rigidly connected to the bolster guide columns spacing intermediate portions of said compression and tension members, said tension member being initially spaced from said bolster guide columns and means for closing up said space for the support of said columns.
3. A side frame comprising compression, tension and bolster column members, said compression and tension members being rigidly united at their ends and increasing in flexibility toward their intermediate portions where bolster guide columns extend from said compression member toward said tension member, the lower ends of said bolster guide columns being rigidly connected by a spring plank seat portion, the intermediate portion of said tension member being separate from and extending beneath said bolster guide columns and spring plank seat portion for supporting the same.
4. A cast side frame comprising compression, tension and bolster column members, said compression and tension members being generally U shape in cross section and integrally united at their ends, said bolster column members spacing intermediate portions of the compression and tension members, connected to said compression member and supported by said tension member.
5. A side frame comprising compression and tension members rigidly united at their ends and tapering in depth therefrom to intermediate portions thereof, bolster columns depending from said compression member, connected at their lower ends by a spring plank seat portion and serving to space intermediate portions of the tension member from said compression member, said tension member extending below but not connected to said spring plank seat portion and bolster columns for supporting the same and so reduced in depth along its supporting portion that it readily flexes under bending stress while hav-

ing ample cross section area for imparting the necessary strength to the frame.

6. A side frame comprising compression, tension and bolster column members, said compression and tension members being rigidly united at their ends and spaced at intermediate portions by the bolster column members, said tension member being relatively deep and substantially U shape in cross section adjacent its junction with the compression member and relatively shallow and substantially rectangular cross section where it extends beneath the bolster column members.

7. A side frame comprising compression and tension members united at each end to a rigid structure adapted to embrace a journal box, the intermediate portions of said members being spaced by a structure comprising bolster guide columns, the lower portion of said structure resting on the intermediate portion of the tension member and adapted for longitudinal movement with respect thereto.

8. A side frame comprising compression, tension and bolster column members, said compression member being rigidly connected to the tension member adjacent the ends thereof and decreasing in depth inwardly therefrom to permit a maximum flexing under load at the center thereof, the intermediate portion of said tension member being adapted for longitudinal movement beneath said bolster column members.

9. A side frame comprising compression, tension and bolster column members, said compression member being rigidly connected to the tension member adjacent the ends thereof and decreasing in depth inwardly therefrom to permit a maximum flexing at the center thereof under load, said bolster column members serving to space intermediate portions of the compression and tension members, being connected at their lower ends by a spring supporting portion and being relatively shallow to accommodate themselves to flexing of the compression member, said spring supporting portion resting upon the tension member and adapted to move longitudinally thereof.

10. A side frame comprising a compression member, a tension member and bolster columns, said bolster columns serving to space intermediate portions of said compression and tension members, and formed with a segmental filler block portion between the lower ends thereof, said filler block portion being initially spaced from said tension member and means for closing up said space to provide for the proper support by said tension member.

11. A side frame comprising compression, tension and bolster column members, said compression member being rigidly connected to the tension and bolster column members, the tension member extending between its

- connections with the compression member beneath the bolster columns and spaced therefrom and means for closing up said space whereby said tension member serves to support said bolster columns.
12. A side frame comprising compression, tension and bolster column members, said compression member being rigidly united to the tension member adjacent the ends thereof and both of said members decreasing in depth toward the center of the frame, the compression members being rigidly connected to the bolster guide columns, said columns serving to space intermediate portions of said compression and tension members, said tension member being cast with a space between the same and said guide columns, means being provided for filling up said space whereby said tension member supports said columns.
13. A side frame comprising compression, tension and bolster column members, said compression and tension members being rigidly united at their ends and increasing in flexibility toward their intermediate portions, bolster guide columns depending from said compression toward said tension member, the lower portions of said bolster guide columns being connected by a segmental spring plank seat portion, the intermediate portion of said tension member extending beneath said bolster guide columns and spring plank seat portion with means therebetween whereby longitudinal slippage of said tension member, when the frame is stressed, is permitted.
14. A side frame comprising compression and tension members united at each end to a rigid structure adapted to embrace a journal box, said structures being formed with vertical sides, horizontal connecting portions and straight sloping portions connecting said sides and horizontal portions, whereby the corners of the openings receiving said journal boxes are cut off, the lower portion of said tension member joining said jaw shaped portions adjacent the junctions between the horizontal and sloping portions.
15. A side frame comprising compression and tension members united at each end to a rigid structure adapted to embrace a journal box, each rigid structure for that purpose being formed with a downwardly opening jaw defined by depending side walls and a substantially horizontal upper wall, said side walls and upper wall being joined by straight sloping portions and the tension member joining said rigid structure below the intersection between extensions of the horizontal and inner depending side walls of the rigid structure whereby the moment arm of forces transmitted to said rigid structures is reduced.
16. A side frame comprising compression and tension members united at each end to a rigid structure adapted to embrace a journal box, the intermediate portions of said members being spaced by bolster guide columns united at their lower ends and resting on the intermediate portion of the tension member, said tension member extending upwardly and outwardly and passing below the virtual intersection between the upper and inner boundaries of the openings for said journal boxes, the corresponding corners of said openings being cut off by sloping wall portions.
- In testimony whereof I affix my signature.
DONALD S. BARROWS.
